UNITED STATES PATENT OFFICE.

EDWARD A. EVERETT, OF NEW YORK, N. Y., ASSIGNOR TO NANDE CORPORATION, A CORPORATION OF NEW YORK.

TRACK-DRILLING MACHINE

1,421,194.

Specification of Letters Patent. Patented June 27, 1922.

Application filed January 15, 1920. Serial No. 351,577.

To all whom it may concern:

Be it known that I, EDWARD A. EVERETT, a citizen of the United States, and resident of 123 Liberty St., New York, in the county of 5 New York and State of New York, have invented certain new and useful Improvements in Track-Drilling Machines, of which the following is a specification.

This invention relates to track drilling machines such as used for drilling railway rails and has for an object the provision of a machine for this purpose operated by power, that is portable, that can be operated, placed in position and replaced, by one man; that is made to roll on one rail of the track, that is balanced on these rollers, that is rapidly brought into and taken out of the operating position, that grips the rail head and holds the drill in alignment and that automatically disengages itself from the rail when released. Other objects will appear from the following specification and drawings in which, Fig. 1 is a side elevation, partly in section, of a track drilling machine embodying my invention; Fig. 2 is a plan view, partly in section and with the engine removed, and Fig. 3 is a front elevation showing certain details of the operating mechanism.

The gasoline engine 11 is adjustably secured to the pads 12 of the frame 14 by the legs 13. The frame 14 is mounted upon rollers 15, on the shafts 41 and have a contour to fit the rail head 16 along which the machine is rolled.

35 The shaft 19 mounted in the bearing 20 of the frame 28 is coupled to the engine by coupling 22. Hand wheel 23 is provided on this shaft for starting purposes, the engine fly-wheel is represented by 21. The belt pulley 40 24 is secured to shaft 19 and by means of belt 29, Fig. 3, drives belt pulley 31. The roller 25, controlled by the handle 26, pivoted at 27, is provided for the purpose of tightening the belt and giving it the tension necessary 45 for the different sizes of drills.

The spur wheel 33 is mounted on the shaft of pulley 31 running in bearing 32. By means of an idler 33^a running on bearing 34, spur wheel 35 is driven from spur wheel 33. By a spline 37, wheel 35 drives the spindle 36 carrying the drill 38. This spindle runs

in the ball bearings 39 and 40. It is an essential feature of a drilling machine of this type that it can be quickly brought into use and quickly taken out of use.

as may be necessary on the approach of a train. I therefore, provide a quick action mechanism for this purpose with a slow feeding mechanism having considerable leverage.

The drill is fed to the operating position by moving the magazine 52 through the sleeve 51 by means of rack 53 engaged by the gear 54. This gear is rotated by the handle 62 having the pivot 54^a corresponding to the pivot of the wheel 54. Latch 64 locks the handle rigid with this gear; this latch is held in engagement by the spring 65 and is released by the latch handle 63.

The quick action is secured by handle 57, pivoted at 58 and terminating in jaw 59^a, which engages the pin 59 secured to the magazine 52. In the operation of the machine, latch handle 63 is raised releasing gear 54, then handle 57 is pulled out thus moving magazine 52 over until the drill 38 engages the rail; latch handle 63 is now released, the feed is regulated by handle 62 and handle 57 is held in position by pin 59. When the drill is to be released, latch handle 63 is raised and spring 60 restores handle 57 against the stop 61 and restores the drill spindle to the position shown. This long slide of the drill adapts the machine to drills of various lengths; it enables the drill to clear the fish plate 18 and the bolt heads, or to position the drill against these parts for drilling the fish plate. It will be noted that handle 62 operating the feed always assumes the same relative position under these varying conditions.

The machine is locked to the rail head by the screw 89^a in frame 14 and members 88 and 89 secured to shaft 85 by brackets 83^a, Fig. 2. These terminate in heads 87 which 95 may be adjusted by screwing members 88 and 89 into brackets 83^a and grip the rail head as shown in Fig. 1. They are brought into the clamping position by depressing pedal 81, through lever 82, secured to bracket 100 83 on shaft 85. Spring 86 holds these clamps normally away from the rail head so that the machine is free to move when pedal 81 is not depressed. The lever 82 may be placed on the other side of the machine and attached to bracket 84. Also secured to shaft 85. It will be noted from Fig. 2 that the screw 89^a is positioned between members 88 and 89, this three position grip of the rail holds the drill in alignment 105 110

ment by a three point support which places the drill at right angles to the rail, and is a matter of importance in a power operated drill. By clamping the rail head from the 5 side toward the drill, the mechanism turns upon the point of screw 89 as a pivot, enabling the drill to be brought into the drilling position with less clamping effort than if the clamp were applied at the opposite side 10 of the rail head. The height of the drill for different sizes of rails is adjusted by the eccentric 42 on the bearing 41 of the rollers 15 and locked in position by the screws 42°.

The foot 70 of the machine supports the 15 outer end and rests upon the ties 17. This foot is pivoted to the frame at 71 and carries the toothed quadrant 72 engaged by the end of handle 73 and held in engagement by spring 74. The ties are frequently irregular 20 and the position of the foot 70 must be adjusted to align the drill at right angles to the rail. For this purpose the handle 73 is raised, unlatching 72 until the foot is positioned, when it is latched again. This 25 enables the foot to be moved out of the way of the ties when the machine is rolled along the track.

The engine is protected by the pipe railing 30 which also serves as a handle for moving the machine along the track or removing it from the track. An extension 91 of this railing forms a rest for the machine when it is off the track.

An oiling system is provided as is essential 35 for the lubrication of a high speed drill. This is conveniently located on the railing of the engine so that the operator may oil the hole that is being drilled while standing erect and while manipulating the operating 40 mechanism of the machine. This consists of an oil tank 95 clamped to the pipe frame as shown and having a discharge pipe 97 terminating in a nozzle 98. When the plunger 96 is operated, the oil in the tank is forced, under pressure, through the discharge 45 pipe and into the hole that is being drilled in the rail as indicated in Fig. 1.

Having thus described my invention, I 50 claim:

1. A comparatively heavy drilling machine for railway track resting upon the track rails, a drilling mechanism incorporated in said machine operating a drill spindle, a handle for sliding said drill 55 spindle into position against the rail to be drilled and an independent handle for feeding said drill when drilling said rail, said feeding and sliding handles being operative without changing the position of said drilling machine relative to said rail.

2. In a track drilling machine, in combination, a carriage mounted upon rollers on 60 said track, a drilling mechanism operating a drill incorporated in said carriage, means for sliding said drill into position against

said rail and spring operated means for retracting said drill without changing the position of said drilling machine relative to said rail and means for feeding said drill when drilling said rail.

70

3. A track drilling machine for railway track resting upon the track rail, a drilling mechanism incorporated in said machine operating a drill spindle, means for sliding said drill spindle toward and away from 75 said rail, a lever arm, said lever arm sliding said drill spindle independently toward and away from said rail, the movements of said spindle being effective without changing the position of said machine relative to said rail. 80

4. In a track drilling machine, in combination, a drilling mechanism including a drill, a magazine carrying said drill and arranged to slide in said mechanism a spring holding 85 said magazine away from said track, a rack on said magazine, a wheel engaging said rack, an operating handle including a latch and means for latching said handle to said wheel and for releasing said handle from said wheel.

5. In a track drilling machine, in combination, a drilling mechanism including a drill, a magazine carrying said drill and arranged to slide on said mechanism, a spring holding 95 said mechanism away from said track, a rack on said magazine, a wheel engaging said rack, a vertical handle for feeding said drill pivoted on the axis of said wheel and a latch on said handle for engaging said rack wheel whereby said handle 100 may be positioned vertically for any position of said drill.

6. In a track drilling machine, in combination, a drilling mechanism including a magazine carrying a drill, said magazine arranged to slide in said mechanism, a rack on said magazine, a wheel engaging said rack, a handle controlling said wheel and feeding 105 said drill, a second handle for sliding said magazine to position said drill against said rail and means for releasing the control of said wheel by said first mentioned handle.

7. In a track drilling machine, in combination, a drilling mechanism including a magazine carrying a drill, said magazine arranged to slide in said mechanism, a rack on said magazine, a wheel engaging said rack, an operating handle controlling said wheel and feeding said drill, a positioning handle moving said magazine through a 115 long fulcrum, a spring controlling said positioning handle to move said drill away from the track rail and means for releasing the control of said wheel by said operating handle.

8. In a track drilling machine, in combination, a carriage mounted upon rollers with eccentric bearings, a drilling mechanism incorporated in said carriage, a foot supporting one side of said mechanism, the 120 125 130

- position of said foot being adjustable; a locking quadrant for positioning said foot and means for positioning said mechanism with relation to the rail of said track by 5 said foot and said eccentric bearings.
9. In a track drilling machine, in combination, a carriage mounted upon rollers on one rail of said track, a drilling mechanism incorporated in said carriage, a foot resting 10 on the ties of said track and supporting one side of said carriage, said foot rotating on an axis and having a notched quadrant and a handle for locking said foot rigid with said mechanism.
- 15 10. A drilling machine for railway track resting upon one rail of said track, clamping means for securing said machine to said rail consisting of a rotatable horizontal shaft parallel with said rail, brackets secured to 20 said shaft, members secured to said brackets by a screw and inclined at an angle to the head of said rail, each of said members ter-
- minating in a rounded end arranged to engage said rail head and adapted to be adjusted by means of said screw to rail heads 25 of various sizes.
11. In a track drilling machine, in combination, a carriage mounted upon rollers on one rail of said track, a drilling mechanism incorporated in said carriage, a drill 30 operated by said mechanism to drill the web of said rail, a jaw engaging the head of said rail opposite said drill, two screws in staggered relation to said jaw engaging the head of said rail on the opposite side, said screws 35 adjustably supported by a bracket on a common shaft, a foot pedal for rotating said shaft and a spring on said shaft to hold said screws away from the rail head.

Signed at New York in the county of New 40 York and State of New York this 13th day of Jany. A. D. 1920.

EDWARD A. EVERETT.
